US0D1106193S

(12) **United States Design Patent** (10) **Patent No.:** **US D1,106,193 S**
(45) **Date of Patent:** ** *Dec. 16, 2025

(54) **DISPLAY DEVICE**

(71) Applicant: **Samsung Display Co., Ltd.**, Yongin-si (KR)

(72) Inventors: **Ki Ho Lim**, Yongin-si (KR); **Duk-Woon Choi**, Yongin-si (KR); **Sung-Hyun Kim**, Yongin-si (KR)

(73) Assignee: **Samsung Display Co., Ltd.**, Yongin-si (KR)

(*) Notice: This patent is subject to a terminal disclaimer.

(**) Term: **15 Years**

(21) Appl. No.: **29/884,425**

(22) Filed: **Feb. 10, 2023**

(30) **Foreign Application Priority Data**

Aug. 12, 2022 (KR) 30-2022-0032891

(57) **CLAIM**

The ornamental design for a display device, as shown and described.

DESCRIPTION

FIG. 1 is a perspective view of the display device, shown in a partially folded and extended state according to the present design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 another perspective view of the display device, shown in an alternate state;

FIG. 9 is another perspective view of the display device, shown in an alternate state;

FIG. 10 is another perspective view of the display device, shown in an alternate state;

FIG. 11 is another perspective view of the display device, shown in an alternate state; and,

FIG. 12 is another perspective view of the display device, shown in an alternate state.

The broken lines indicate unclaimed portions of the article that form no part of the claimed design.

1 Claim, 12 Drawing Sheets
